UNITED STATES PATENT OFFICE.

ELMER F. REINHARDT, OF OWENSBORO, KENTUCKY.

MUFFLER.

Application filed September 12, 1923. Serial No. 662,243.

To all whom it may concern:

Be it known that I, ELMER F. REINHARDT, a citizen of the United States, residing at Owensboro, in the county of Daviess and 5 State of Kentucky, have invented certain new and useful Improvements in Mufflers, of which the following is a specification.

This invention is a device for muffling the sound of explosions and is intended primarily for use upon the exhausts of internal combustion engines, although it may be used upon firearms and wherever it is desirable to muffle the sound of an explosive exhaust. The invention provides a novel, 10 simple and compact structure by the use of which the escaping gases will be permitted to expand within a closed chamber and then permitted to pass out after losing their explosive force. The invention is illustrated 15 in the accompanying drawing and will be hereinafter fully set forth.

In the drawing:

Figure 1 is a central longitudinal section through a muffler embodying my improvement;

Fig. 2 is a transverse section on the line 2—2 of Fig. 1;

Fig. 3 is an end elevation, and

Fig. 4 is a detail perspective view illustrating the joint between one of the muffler tubes and a head of the outer casing.

In carrying out my invention, I employ a cylindrical body 1 which may conveniently be of sheet metal and is provided intermediate its ends with a partition 2 spot-welded at its periphery to the inner circumference of the cylinder and dividing the body into end compartments A and B. The ends of the cylinder are fitted in annular 35 grooves 3 in heads 4 and 5 which are similar in their general contour and construction and are preferably metallic castings. The heads are provided centrally with openings aligned with a similar opening in the partition 2 through which is inserted a long bolt or connecting rod 6 equipped with a head 7 at one end bearing against the outer surface of the adjacent head 4 and at its opposite end equipped with a nut 8 adapted 40 to be turned home against the head 5. When the nut is full turned home, the heads will be clamped together so as to secure the cylindrical body in place, as will be readily understood upon reference to the drawing.

The heads are provided on their inner surfaces, preferably upon their vertical diam-

eters, with eccentrically located annular bosses 9 receiving the ends of muffler tubes 10 and 11, the ends of the tubes abutting seats or shoulders defined by the bosses so that they will be clamped in place when the connecting rod 6 is fastened. The head 4 has an opening formed therethrough concentric with the upper tube 10, and this opening receives the end of the exhaust pipe 12 of the engine. To secure the said exhaust pipe firmly in position, a tapered flange 13 is fitted about the same and engaged in the opening in the head so that, if the flange be driven home, the exhaust pipe will be firmly secured, and it is to be noted that the external diameter of the exhaust pipe is approximately equal to the internal diameter of the upper muffler tube 10 so that the end of the pipe may enter the end of the tube, as shown clearly in Fig. 1, and the exhaust gases discharged directly into the tube. To secure the flange 13 in place, it is provided with lateral extensions or lugs 14 through which cap screws 15 are inserted to be engaged in openings 16 provided therefor in the head whereby the flange will be easily and securely driven home. The head 5 is imperforate at the end of the upper muffler tube 10, except for the provision of a small internally threaded passage 17 in which is engaged a threaded stem 18, the outer end of the said stem being of angular cross section, as indicated at 19, whereby it may be engaged by a wrench or other turning tool. The stem 18 passes into the end of the tube 10 and carries a plunger 20 which fits closely within the tube so as to form a closure therefor. A lock nut 21 is mounted upon the stem and is adapted to be turned home against the external boss 22 upon the head 5 concentric with the internal boss 9 so that the stem and the plunger will be effectively secured in any position of adjustment. The muffler tubes 10 and 11 pass through openings provided therefor in the partition 2 so that they are supported intermediate their ends by the partition as well as at their ends by the heads 4 and 5, and this partition 2 divides the cylindrical body 1 into two expansion chambers, as will be readily understood. At opposite sides of the partition, the upper muffler tube 10 has its side portions provided with longitudinal slots indicated respectively by the numerals 23 and 23' and through which the gases escape into the expansion chambers A and B. It should

be noted that the slots 23' are shorter than the slots 23. By loosening the lock nut 21 and then rotating the stem 18, the plunger 20 may be set at any desired point in the 5 length of the upper muffler tube 10 so that the effective length of the tube may be varied, and this adjustment of the plunger will, of course, in some instances reduce the effective length of the slots 23'. This 10 adjustability or variability of the upper muffler tube is advantageous in applying the muffler to different engines inasmuch as engines of the same rating, in actual practice, do not always agree in every detail in 15 their operation and it is frequently necessary to vary the adjustment of the muffler when applying it to an engine of a known rating.

The lower muffler tube 11 is provided in 20 its sides with longitudinal slots 24 and 24' disposed at opposite sides of the partition 2. It should be noted that the slots 24 and 24' are all shorter than the slots of the inlet tube 10 and that the slots 24 through 25 which the gases pass from the compartment A are shorter than the slots 24'. The front end of the said muffler tube 11 is closed by the head 4 but the head 5 is provided with an opening 25 formed in alignment with the 30 muffler tube 11 and threaded so that the front end of a discharge pipe 26 may be secured in this opening. The diameter of the pipe 26 should be at least equal to the diameter of the exhaust pipe 12. In Figs. 35 1 and 4, I have shown the front end of the muffler tube 11 as provided with a notch 27 adapted to engage a lug 28 upon the inner circumference of the boss 9 so that, in assembling the tube, the slots 24 therein will 40 be brought into proper position without liability of shifting from that position during the assembling of other parts of the muffler. The rear end of the tube 10 is constructed in the same manner so that it 45 may be accurately placed when assembling the several parts. It is also to be understood that, if desired, the plunger 20 and its cooperating parts may be shifted to the front end of the muffler tube 11 and an 50 opening formed through the head 5 in alignment with the upper muffler tube to permit a cut-out to be mounted in the upper muffler tube.

In use, the exhaust gases flow from the 55 exhaust pipe 12 into the upper muffler tube 10 and pass out of this tube through the slots 23 and 23' into the compartments A and B. As the gases pass through the slots of the tube 10, they enter the expansion 60 chambers defined by the cylindrical body 1 and impinge against the inner surface of the cylindrical body which is eccentric to the muffler tubes. The gases at once expand and a part of them assumes the form of a thin 65 film traveling at high speed over the inner

surface of the body 1. The gases may more readily pass from the tube 10 into the compartment A as the slots 23 are longer than the slots 23' but they can more readily pass out of the compartment B as the slots 24' 70 are longer than the slots 24 and in fact are nearly as long as the slots 23'. The gases passing through the slots 24' into and through the rear end portion of the tube 11 will therefore create a suction which will cause the gases in the compartment A to be quickly drawn through the slots 24 and rearwardly through the tube 11. Of course, the gases which enter the muffler tube 11 will flow therefrom into and through the discharge pipe 26 from which they emerge into the open air. If the device be mounted upon an automobile engine, for instance, the travel of the vehicle will create a suction 80 through the discharge pipe which will aid in the operation of the muffler and will increase its efficiency.

My device is exceedingly simple and compact in the construction and arrangement of its parts, may be produced at a low cost, and 90 readily applied wherever it is to be used. The several parts may be easily and quickly assembled or disassembled so that, if in the course of time, some parts should be broken or worn out, a new part may be substituted 95 therefor without requiring the use of skilled labor.

Having thus described the invention, what is claimed as new is:

1. In a muffler construction, a casing having a tubular body circular in cross section and heads at the ends of said body, a partition in said casing intermediate the length of said body and dividing the casing into forward and rear compartments, and inlet and exhaust tubes disposed longitudinally in said casing with their ends engaged with said heads and their intermediate portions passing through said partition, the inlet tube having its inlet end registering with an opening in one of the heads and the exhaust tube having its outlet end registering with an opening in the other head and said tubes being provided in the forward and rear compartments with slots formed in their opposed side portions and extending longitudinally of the tubes.

2. In a muffler construction, a casing having a tubular body circular in cross section and heads at the ends of said body, a partition in said casing intermediate the length of said body and dividing the casing into forward and rear compartments, and inlet and exhaust tubes disposed longitudinally in said casing with their ends engaged with said heads and their intermediate portions passing through said partition, the inlet tube having its inlet end registering with an opening in one of the heads and the exhaust tube having its outlet end registering with an opening in the other head.

an opening in the other head and said tubes being provided in the forward and rear compartments with slots formed in their opposed side portions and extending longitudinally of the tubes, the slots in the exhaust tube being shorter than the slots in the inlet tube.

3. In a muffler construction, a casing having a tubular body circular in cross section and heads at the ends of said body, a partition in said casing intermediate the length of said body and dividing the casing into forward and rear compartments, and inlet and exhaust tubes disposed longitudinally in said casing with their ends engaged with said heads and their intermediate portions passing through said partition, the inlet

tube having its inlet end registering with an opening in one of the heads and the exhaust tube having its outlet end registering with an opening in the other head and said tubes being provided in the forward and rear compartments with slots formed in their opposed side portions and extending longitudinally of the tubes, the inlet tube having the slots in its forward end portion longer than the slots in its rear end portion and the exhaust tube having its slots shorter than the slots of the inlet tube and the slots in its forward end portion shorter than the slots in its rear end portion.

In testimony whereof I affix my signature.

ELMER F. REINHARDT. [L. S.]
